United States Patent Office.

JOSEPH W. HILDRETH, OF BOSTON, MASSACHUSETTS.

Letters Patent No. 76,914, dated April 21, 1868.

IMPROVED LEATHER-POLISHING MACHINE.

The Schedule referred to in these Letters Patent and making part of the same.

TO ALL TO WHOM THESE PRESENTS SHALL COME:

Be it known that I, JOSEPH W. HILDRETH, of Boston, in the county of Suffolk, and State of Massachusetts, have invented a new and useful Improvement in Machines for Performing the Operation of Glassing Leather, as it is termed; and do hereby declare the following to be a full, clear, and exact description thereof, due reference being had to the accompanying drawings, making part of this specification, and in which—

Figure 1 is a vertical, central, and longitudinal section, and

Figure 2 a vertical and transverse section of a "leather-glassing" or polishing machine, with my invention applied thereto.

Figure 3, a side elevation of a portion of the machine, showing the elastic bearing to be hereinafter described.

This invention is an improvement in that class of machines which perform the operation of polishing or "glassing" leather, as it is termed, such machine consisting mainly of a vibrating-arm or lever provided with a "glassing" or polishing-tool affixed to its lower end, and traversing a concave bed applied to an elastic or yielding foundation, the leather to be polished being placed upon such bed and operated upon by the polishing-tool in a manner well known to persons skilled in this branch of the industrial arts.

In the accompanying drawings, A denotes a metallic bed, concave upon its upper surface, and resting upon and supported at each end by an elastic cushion or spring, a a, the bed thus supported being upheld by a suitable framework, b, applied to the floor of an apartment or building in which the machine is situated.

A vibrating-arm or lever, c, is suspended at its upper end from the arm d of a gallows-frame, e, making part of the framework b before mentioned, the lower end of the arm c being pivoted to a swivelling-block or tool-holder, f, this tool-holder being in turn affixed to the front end of a reciprocating connecting-rod, g, whose opposite end is jointed to a crank or crank-wheel, h, fixed to a horizontal shaft, i, upheld by an upright standard, j, fixed to the floor of the apartment, a pulley, k, being applied to the shaft i for putting it and the crank in rotation. A suitable glassing-tool is affixed to or carried by the holder f.

The rotation of the crank-wheel h causes a reciprocating rectilinear of the tool f, across the surface of the bed A, and from end to end thereof, in order to polish or "glass" a side of leather, when laid thereon.

The above-described arrangement of parts is the usual construction of machines of this class, and does not cover my invention. The objection to it is that as the polishing-tool approaches the centre of the bed A, the pressure upon the leather of course increases as the power of both springs exerts its full action thereon.

As the polishing-tool recedes in either direction from the centre of the bed, the pressure is exerted by one spring, and removed to a great extent from the opposite one, the consequence of which is that the pressure upon the leather is unequally distributed, and the leather becomes distended or baggy and reduced in thickness in its central portion.

My invention is intended to obviate this objection by equalizing the distribution of pressure upon the finishing-bed and leather, and in carrying out such invention, I make the point of suspension of the vibrating arm c an elastic one, in order to accomplish this.

The mode shown in the accompanying drawings for applying the elastic bearing, is composed as follows:

The lever c is upheld by a horizontal cross-bar, l, which extends laterally through its upper end, the outer ends of such cross-bar extending into guides or slots, m m, made through the side bars a' a' of the arm d, before mentioned, the lever c swinging between the two. A spring, n, composed of India rubber, or other suitable material, is placed upon the top of each end of the cross-bar l, and within the slots m m, as shown in fig. 3 of the drawings.

A set-screw, o, is screwed through a cap-plate, p, applied to each bar a', and over and closing the slots m m, such set-screws pressing down upon a metallic plate, q, placed over the top of each spring n n, and serving to regulate pressure of such springs upon the cross-bar l.

If considered necessary or desirable, metallic blocks, recessed for reception of the end of the springs n n,

may be interposed between the cross-bar *l* and such springs, to retain them in place, the blocks being formed with splines or projections upon each, to slide in grooves made in the inner faces of the slots *m m*.

By employing a machine constructed in accordance with my invention above described, the pressure, and consequently the action and effect of the polishing-tool, are nearly the same upon all parts of the bed *A*, and the leather placed upon it, thus greatly improving the general appearance of the leather, and producing a uniform and even surface, and adding to its general texture and wearing qualities, as well as rendering it of a smooth, general surface, and facilitating the convenience of cutting it into shoes.

Having described my invention, and the manner in which the same is or may be carried into effect, what I claim, and desire to secure by Letters Patent, is—

In a machine such as described, the combination, with the yielding bed upon which the leather is placed, of the vibratory lever to which the glassing-tool holder is attached, provided at its point of suspension with an elastic and yielding bearing, substantially in the manner and for the purposes herein shown and set forth.

J. W. HILDRETH.
